RADIO ANTENNA

Vern M. Wintermute, North Plainfield, N. J., assignor to Lyte Parts Company, Plainfield, N. J., a corporation of New Jersey

Application May 22, 1948, Serial No. 28,712

1 Claim. (Cl. 250—33)

1

This invention relates to improvements in antenna structures. It is particularly directed to an improved antenna for the reception of signals of frequencies associated with television and frequency modulation broadcasting.

It is the primary object of the present invention to provide an antenna which will accommodate all of the presently designated television channels and frequency modulation bands.

A further object of my invention is to provide a directional dipole antenna arranged for the higher frequencies and lower frequencies in television broadcasting, with which is associated a novel and useful reflector assembly.

A still further object of my invention is to provide an antenna for television and frequency modulation signals which is complete with all necessary parts, which will give trouble-free service, and which is arranged for ready installation on a suitable antenna mast.

The antenna of the present invention is similar in some respects to that which is shown in an earlier application, Serial Number 20,618, for Television antenna, filed April 13, 1948; in which application I am a co-inventor with George E. Zellinek, now abandoned.

In the drawings,

Figure 1 is a perspective view showing the antenna structure of my invention supported on an antenna mast, shown fragmentarily, and

Figure 2 is a cross-section view taken on the lines 2—2 of Figure 1.

Referring to the two views of the drawing, the antenna of my invention includes a pair of reversely folded tubular conducting metal dipole elements 10, coplanar in part with respect to each other on an electrical insulating panel 11, the latter of which is affixed by means of a flat bracket 12 to one end of a horizontal tubular cross-arm or stand-off tube 13. Cross-arm 13 is, in turn, pivotably fixed to the top end of a suitable antenna mast 14, as by the use of T bracket 15 located approximately midway of the length of the cross-arm. A reflector assembly designated generally at 16 is affixed to the end of the cross-arm 13 opposite to that of the dipole assembly.

The folded dipole loops 10 are engaged by and held in rolled edges of thin flat sheet metal mounting plates 17 for fastening with machine screws, to panel 11, and they are of suitable combined length for optimum reception of signals in the lower frequency channels assigned to television and to frequency modulation in the frequency range between 44 and 108 megacycles.

2

Loops 10 are, additionally, angularly bent and staggered whereby their free, inwardly directed, open ends cross each other in front of panel 11 to form, in effect, a V type antenna for the reception of signals in the higher frequency television channels in the frequency range between 174 and 216 megacycles. Separation of the free open ends of loops 10 is maintained by the engagement therewith of suitable strips of insulating material 18.

Three parallel tubular multiple piece metallic reflector rods 20, 20', and 20'' constitute the principal elements of the reflector assembly 16, which rods are centrally secured to a bracket 12' fixed to the end of cross-arm 13. The reflector elements are co-planar and horizontally disposed corresponding in elevation with the dipole; and it will be noted that they are graduated in length with the longest rod 20 in the topmost position. Stability for the free ends of the reflector rods is maintained with insulating strips 21 which are drilled to fit over the rods and serve to tie them together and thus assist in preventing sagging and bending.

I prefer to make the folded dipole of a length which is approximately one-half wavelength at the geometric center of the lower frequency television band, and of suitable proportion so that I avoid any sharp peaks in a curve of signal response of my antenna compared with a tuned dipole. For the higher frequency channels, the combined length of the legs of the V corresponds approximately to one half wavelength at the geometric center of the band. The reflectors 20, 20' and 20'' may each correspond in length to one half wavelength in a particular lower frequency channel, as for example in channels number 4, 5, and 6. Thus, as will be understood by those skilled in the art, I obtain maximum signal response over the range where it is most desired.

Transmission line lead-in wiring 25 of suitable characteristics is used, preferably comprising a co-axial cable and matching stub, with the shield 45 of the co-axial cable terminating in the mounting plate 17 for the dipole element on the left hand side and the "hot" wire of the co-axial cable crossing over for termination with the matching stub in the mounting plate 17 for the right hand dipole element. An insulator 26 fastened to the depending end of bracket 12 and a second insulator 26' serve to position and insulate the cable and the matching stub as the wiring is directed downwardly from the antenna, and suitable provision is made immediately below insula-

tor 26' to ground the shield of the co-axial cable and the matching stub to the antenna mast.

It will be appreciated by those who are skilled in the art that certain optional or necessary changes in the arrangement of parts and in their specifications may be substituted for those illustrated, depending upon the type and specifications of the receiving set with which my improved antenna is used. I do not, therefore, wish that the invention be limited to the specific apparatus other than as particularly pointed out in the subjoined claim.

Having thus described my invention in a preferred embodiment of the principles thereof, I claim:

In an antenna for the reception of television signals or the like, in combination, a pair of antenna elements; each element consisting of a linear conductor folded back on itself to provide a pair of parallel legs having a closed end and an open end and angularly formed so that the closed end with a substantial portion of the linear conductor lies in one plane while the open end and a substantial portion of the remainder of the conductor lies in an intersecting plane, the 25

closed ends of the antenna elements being directed oppositely outwardly in an identical plane and the open ends of the conductors being interleaved and crossing each other on one side of said identical plane; metallic brackets carrying the parallel legs of each conductor element adjacent the location of angular formation and providing electrical connection therebetween, an insulating panel member supporting said conductor carrying brackets whereby the antenna elements may be maintained in said interleaved, planar relationship, and a transmission wiring connection on each conductor carrying bracket.

VERN M. WINTERMUTE.
